UNITED STATES PATENT OFFICE

WILLIAM H. GREEN, OF BROOKLYN, NEW YORK, ASSIGNOR TO VADS CO SALES CORPORATION, OF NEW YORK, N. Y., A CORPORATION OF DELAWARE

DESIGN FOR A TOILET ACCESSORY CONTAINER

Application filed May 23, 1931. Serial No. 39,938. Term of patent 14 years.

To all whom it may concern:

Be it known that I, WILLIAM H. GREEN, a citizen of the United States, residing at Brooklyn, county of Kings, city of New York, and State of New York, have invented a new, original, and ornamental Design for Toilet Accessory Container, of which the following is a specification, reference being had to the accompanying drawings, forming a part thereof.

I claim:

The ornamental design for a toilet accessory container as shown.

WILLIAM H. GREEN.
